UNITED STATES PATENT OFFICE

111,153

DESIGN FOR A RESERVOIR DESK STAND OR SIMILAR ARTICLE

Robert Rose, Chicago, Ill., assignor to W. A.
Sheaffer Pen Company, Fort Madison, Iowa, a corporation of Delaware

Application July 15, 1938, Serial No. 78,499

Term of patent 7 years

To all whom it may concern:

Be it known that I, Robert Rose, a citizen of the United States, residing at Chicago, in the county of Cook and State of Illinois, have invented a new, original, and ornamental Design for a Reservoir Desk Stand or Similar Article, of which the following is a specification, reference being had to the accompanying drawing, forming a part thereof.

In the drawing:

Fig. 2 is a side elevational view of Fig. 1; and
Fig. 3 is a front elevational view of Fig. 1.

I claim:

The ornamental design for a reservoir desk stand or similar article, substantially as shown.

ROBERT ROSE.
